[57] CLAIM

The ornamental design for electrostatic copying machine, as shown and described.

DESCRIPTION

FIG. 1 is a front and top-right perspective view of an electrostatic copying machine showing my new design; FIG. 2 is a front elevational view thereof; FIG. 3 is a top plan view thereof; FIG. 4 is a right side elevational view thereof; FIG. 5 is a left side elevational view thereof; FIG. 6 is a bottom plan view thereof; FIG. 7 is a rear elevational view thereof; and FIG. 8 is a front and top right perspective view thereof with the paper feeding receiving trays in place. In FIGS. 1-7, the paper feeding, guiding and receiving trays have been omitted for ease of illustration and clarity.

FIG. 1

FIG. 2

FIG. 3

FIG. 4

FIG. 5

FIG. 6

FIG. 7

FIG. 8
